UNITED STATES PATENT OFFICE.

HENRY G. VOIGHT, OF NEW BRITAIN, CONNECTICUT, ASSIGNOR TO RUSSELL AND ERWIN MANUFACTURING COMPANY, OF NEW BRITAIN, CONNECTICUT.

NIGHT-LATCH.

SPECIFICATION forming part of Letters Patent No. 720,986, dated February 17, 1903.

Application filed November 18, 1902. Serial No. 131,825. (No model.)

To all whom it may concern:

Be it known that I, HENRY G. VOIGHT, a citizen of the United States, residing at New Britain, in the county of Hartford and State 5 of Connecticut, have invented certain new and useful Improvements in Night-Latches, of which the following is a specification.

My invention relates to improvements in night-latches; and the objects of my improvement are simplicity and economy in construction and convenience and efficiency of operation.

In the accompanying drawings, Figure 1 is an elevation of that side of my latch which 15 is designed to rest upon the surface of the door. Fig. 2 is a like view of same with the cap-plate and attached lock portion removed. Figs. 3, 4, and 5 are like views with a portion of the latch-bolt body broken out and 20 with the moving parts in various positions. Fig. 6 is a like view of a portion of the case with a transverse section of the knob-spindle. Fig. 7 is a sectional elevation, the plane of section being indicated by the line $x-x$, 25 Fig. 1.

A designates the main portion of the case, and 8 is the cap-plate thereof. Upon this cap-plate, mainly within the cylinder 9, is the lock portion of the latch, the same being designed 30 to be operated by a key from the outside. At the inner end of the cylinder 9 and within the case is the cam or wing 10 of the lock portion that acts upon the cross-plate of the latch-bolt 12 for withdrawing the bolt by 35 the key. All of this lock portion may be of any ordinary construction.

The reference-numeral 12 is placed on the body of the latch-bolt to indicate the said bolt generally, while 13 is the head of the said 40 bolt at the outer end thereof, and 11 is the cross-plate at the opposite end. A spring 14 surrounds a portion of the body of the latch-bolt 12 and acts against the head 13 at one end and the plate 15 at the other, the said 45 plate 15 resting against the studs 16 of the case, whereby the latch-bolt may be forced inwardly by pressure on the cross-plate and outwardly by the said spring, all as in prior latches of this class.

50 The cross-plate 11 of the latch-bolt constitutes, in effect, shoulders on the latch-bolt

and is acted upon by the two-armed latch-hub 17. The arm 18 of this hub is the longer arm, and in addition to its radial edge and outer end is provided with a cam-face or cam-rise 55 19, followed by a bearing edge 20, which is preferably concentric to the latch-hub. This cam-face and bearing edge are for acting upon the pin 21 or other fixed projection on the case. The arm 22 of the hub 17 is the shorter 60 arm for acting on the cross-plate by its radial edge and is also provided with the stop-lug 23, that projects transversely to the length of the said arm sufficiently to act on the body of the latch-bolt. As shown, the 65 hub is supported on a short shaft or spindle 24, Fig. 6, that takes its bearings in only one of the latch-plates—that is, the plate which forms the broad side of the main portion of the case A. This bearing 25, Fig. 6, instead 70 of being a round hole to fit the knob-spindle 24 on all sides is elongated on the inner side, so that the said spindle and attached latch-hub may move bodily inward transversely to the axis of the said hub and in the direction 75 of the inward movement of the latch-bolt. The outer end of the knob-spindle is provided with any suitable operating device—as, for example, the knob 26.

When the parts are in the position shown 80 in Figs. 1, 2, and 7, the latch-bolt may be withdrawn or forced inwardly by forcing the cam or wing 10 of the lock portion against the cross-plate 11 by means of a key from the outside in the ordinary manner, or the latch-bolt 85 may be withdrawn by forcing either arm of the latch-hub against the said cross-plate by turning the knob 26 on the inside of the door. When the said knob is turned so as to carry the longer arm 18 against the cross-plate 11, the stop-lug 23 on the shorter arm 22 comes into engagement with the body of the latch-bolt and stops the movement of the said hub about the time that the latch-bolt head 13 is fully withdrawn, all as illustrated 95 in Fig. 3. Upon releasing the knob the spring 14 acts to force the parts into the position shown in Fig. 2. When the knob is turned in the direction to force the shorter arm 22 against the stop-plate 11, the bolt is forced 100 inwardly until the head 13 is wholly withdrawn—that is, so as not to project at all.

The cam-rise 19 engages the fixed pin 21 on the case with a tendency to stop the parts in the position illustrated in Fig. 4 and does stop the parts in that position when the 5 knob is turned in the natural way without any special effort to turn it harder than is necessary to effect this movement. Upon releasing the knob when in this position the spring 14 restores the parts to the position 10 shown in Fig. 2. When, however, it is desired to disconnect the night-latch entirely—that is, set it so that the latch-bolt will stay in its withdrawn position until it is purposely forced out again—then the knob is turned in 15 the direction to force its shorter arm 22 against the stop-plate with a special effort to carry the cam-rise beyond the fixed pin or projection. The said rise acts as a cam and forces the entire latch-hub and attached parts bodily 20 inward in the direction of the inward movement of the latch-bolt, the enlarged spindle-bearing permitting the hub and connected parts to thus move bodily in the transverse direction of the axis of the said hub. After 25 the cam-rise passes the pin 21 the bearing edge which follows permits the hub to be turned so as to bring the latch-hub arms substantially in alinement with the latch-bolt, in which position the movement of the hub is 30 arrested by the stop-lug 23 engaging the body of the latch-bolt at a point adjacent to the cross-plate 11, all as shown in Fig. 5. In Fig. 5 the broken-line circle indicates the normal position of the hub 17. The latch-bolt is 35 now more than fully withdrawn, or, in other words, a little farther than it would ordinarily be withdrawn merely for opening the door. The friction of the shorter arm 22 on the cross-plate and that of the bearing edge 40 20 on the pin 21 when the parts are in the position shown in Fig. 5 is sufficient to retain

the parts in this position as long as may be desired. When it is desired to again put on the night-latch, it is only necessary to turn the knob back from the position shown in Fig. 5 to that shown in Fig. 4, and the spring will return the parts to their normal position, as shown in Fig. 2.

I claim as my invention—

1. In a night-latch, the combination of a latch-bolt and its spring with a two-armed operating-hub having the cam-rise 19, a fixed projection for being engaged by the said cam-rise, a spindle for the said hub and a case having a bearing for the said spindle which permits the said hub and connected parts to move transversely to the axis of the said hub under the action of the said cam-rise.

2. In a night-latch, the combination of a latch-bolt and its spring with a two-armed operating-hub having the cam-rise and a stop-lug on the said hub, a fixed projection for being engaged by the said cam-rise, the said stop-lug being arranged to act on the body of the latch-bolt, a spindle for the said hub and a case having a bearing for the said spindle which permits the said hub and connected parts to move transversely to the axis of the said spindle under the action of the said cam-rise.

3. In a night-latch, the combination of a latch-bolt and its spring with a two-armed operating-hub, and a stop-lug mounted on and moving with the said hub, the said lug being arranged relatively to the body of the said latch-bolt for coming in contact therewith, when the said hub is turned in either direction.

HENRY G. VOIGHT.
